United States Patent Office.

WILLIAM H. BURKE, OF BRIGHTON, MASSACHUSETTS, ASSIGNOR TO HIMSELF AND JAMES E. WILSON, OF SPRINGFIELD, MAINE.

Letters Patent No. 75,518, dated March 17, 1868.

IMPROVEMENT IN CAR-BRAKES.

The Schedule referred to in these Letters Patent and making part of the same.

TO ALL PERSONS TO WHOM THESE PRESENTS MAY COME:

Be it known that I, WILLIAM H. BURKE, of Brighton, in the county of Middlesex, and State of Massachusetts, have invented a new and useful Brake-Mechanism for Railway or various other Wheel-Carriages; and I do hereby declare the same to be fully described in the following specification, and represented in the accompanying drawings, of which—

Figure 1 is a longitudinal section, and

Figure 2 an under side view of a railway-car truck provided with my invention.

In such drawings, A denotes the platform, B B B B the wheels, and C C the axles of such truck. Aside of the periphery of each wheel, and from the bearing-frame *a*, a friction-brake or rubber, D, is suspended by a staple, *b*, projecting from the said frame. Four cams E E E E, fixed upon two shafts F F, arranged parallel to the axles, are disposed with respect to the brakes in manner as represented. The shafts F F have their journals supported in hangers *ddd d*. Each shaft, F, has one of the worm-gears G G applied to it, and such gears engage with two worm-screws, H H, fixed on a horizontal shaft, I, extending longitudinally through the truck-frame, and supported by hangers or brackets K K, arranged as shown in figs. 1 and 2. At either or each end of the shaft I is a bevel-gear, L, which engages with another such gear, M, carried by a vertical shaft, N, arranged at or near the end of the carriage, and provided with a hand-wheel, D'. By laying hold of and revolving the hand-wheel, the cams may be revolved simultaneously against all the brakes, so as to force them against the peripheries of all the wheels. By turning back the hand-wheel the wheels may be relieved from such pressure of the brakes.

The advantage of my brake-mechanism, in comparison to the ordinary lever and chain-mechanism for actuating the brakes of railway-cars, is that mine requires no ratchets and pawls to hold the brakes in contact with the wheels. Furthermore, the rubbers or brakes can be forced against the wheels with any degree of pressure that may be required.

I claim the combination and arrangement of the three shafts F F I, their screws H H, worm-gears G G, cams E, and the bevel-gears L M, and vertical hand-wheel shaft N; arranged at either or each end of the carriage, and with respect to the brakes D, substantially in manner as specified.

WM. H. BURKE.
